Primary Examiner — Mary Ann Calabrese*(74) Attorney, Agent, or Firm* — Prakash Nama; Global IP Services, PLLC(57) **CLAIM**

The ornamental design for a combined table with heater, as shown and described.

DESCRIPTION

FIG. 1 is a front elevational view of combined table with heater showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

The broken lines shown in the combined table with heater form no part of the claimed design.

It is certified that error appears in the above-identified patent and that said Letters Patent is hereby corrected as shown below:

On the Title Page

Item (71) The Applicant's name should be corrected from:
Zhejiang Jiangxing Electric Appliance Co., Ltd.

To:
Zhejiang Jiaxing Electric Appliance Co., Ltd.

Signed and Sealed this
Tenth Day of September, 2024
Katherine Kelly Vidal
Director of the United States Patent and Trademark Office
